CLAIM

The ornamental design for a sparkling machine, as shown and described.

DESCRIPTION

FIG. 1 is a front elevational view of a sparkling machine according to my design;

FIG. 2 is a rear elevational view thereof;

FIG. 3 is a left side elevational view thereof;

FIG. 4 is a right side elevational view thereof;

FIG. 5 is a top elevational view thereof;

FIG. 6 is a bottom elevational view thereof; and,

FIG. 7 is a front, right perspective view.

Any dashed lines in the drawings depict unclaimed subject matter and form no part of the claimed design.
